(57) **CLAIM**

The ornamental design for inflatable paint booth, as shown and described.

DESCRIPTION

FIG. 1 is a front elevational view of inflatable paint booths; FIG. 2 is a back side elevational view thereof;

FIG. 3 is a left view thereof.

FIG. 4 is a right view thereof.

FIG. 5 is a top view thereof; and,

FIG. 6 is a bottom view thereof.

The broken lines depict portions of the inflatable paint booth that form no part of the claimed design.
